UNITED STATES PATENT OFFICE

2,453,026

CIGARETTE EXTINGUISHER AND ASH TRAY

Robert M. Maney, Oklahoma City, Okla.

Application February 26, 1945, Serial No. 579,778

4 Claims. (Cl. 231—235)

1

This invention relates to a combination ash tray and extinguisher for cigarettes.

Among the objects of the invention are to provide a simple and practical means for quickly extinguishing a cigarette, so as to prevent it from continuing to smoke, and for containing ashes and butts so that they will be completely concealed.

In order that the invention may be readily understood, reference is had to the accompanying drawing, forming part of this specification and in which:

Fig. 1 is a plan view of one form of my improved extinguisher and ash tray.

Fig. 2 is a vertical longitudinal section, substantially on the line 2—2 of Fig. 1, looking in the direction of the arrows.

Fig. 3 is a transverse section substantially on the line 3—3 of Fig. 1, looking in the direction of the arrows, and showing in dotted lines the position to which the parts can be moved.

Fig. 4 is a plan view showing a modified construction, and

Fig. 5 is a longitudinal section substantially on the line 5—5 of Fig. 4, looking in the direction of the arrows.

Referring to the drawing in detail, and more particularly first to Figs. 1—3 thereof, my improved ash tray comprises a receptacle or container 1, shown as of substantially rectangular form, and of a length at least equal to that of a cigarette. Secured to one end of this receptacle may be a match holder 2.

A horizontal shaft 3 extends longitudinally across the top of the receptacle and is supported at one end in bearings 4, and at the other end in a notch 5 formed in the upper edge of the receptacle. This shaft has secured to one end a knob 6, or the like, by which it may be rotated.

Rigidly secured to this shaft, as by soldering or welding, is a cover plate 7. As shown in Fig. 1, this plate fits snugly within the upper edge or top of the receptacle 1, and may be tilted or reversed by turning the shaft 3 by means of the knob 6. The shaft 3 is so positioned as to substantially bisect the cover plate, whereby such cover plate would be substantially balanced on the shaft.

Set into and extending through the cover plate at one side of the shaft are one or more funnels 8. In the particular embodiment illustrated, four of such funnels are shown. They are preferably of inverted conical shape, extending through openings in the plate 7, being located partly below and partly above such plate.

2

The lower small end of each of these funnels is open as shown at 9, but this opening is substantially smaller than the diameter of a cigarette, so that a cigarette will not pass through the same.

In use, when it is desired to extinguish a cigarette, it is simply dropped into one of these funnels, so that the lighted end enters the lower portion thereof. By reason of being closely confined in the lower portion of the funnel, the cigarette is quickly extinguished and the loose ashes fall down through the opening 9 to the receptacle 1. It is intended that the cigarette be simply placed lightly in the funnel without any pushing or forcing. Thus, not having been mashed or deformed in any way, it may be removed from the funnel and relighted as often as desired. On the other hand, when only a short butt remains, the cover 7 may be swung on the shaft into reversed position, as shown in Fig. 3, so that the butt is dumped into the receptacle.

It will be understood that the weight of the funnels 8 serves to unbalance the cover plate and tends to rotate it about the axis of the shaft. Suitable stops 11 are, however, provided to support the cover in a substantial horizontal position, and the weight of the funnels serves to maintain the cover plate in engagement with the stops.

In addition, if desired, I may place a small spring 12 around the shaft 3, as shown in Figs. 1 and 2, such spring being anchored at one end to the shaft, and at the other end to the receptacle, as indicated at 13. This spring is constructed to urge the cover plate against the stops 11, as will be understood.

At the side of the shaft 3, opposite the funnels 8, the cover plate is preferably shaped to form a trough or holder 10, in which cigarettes may be placed.

In Figs. 4 and 5, I have illustrated a somewhat modified construction. In this construction the cover plate 7 is provided with openings 14. Beneath each of these openings is disposed a funnel, divided longitudinally into two separable sections 16, 17, each of these sections being independently pivoted at its upper end on blocks 15, as indicated at 18 in Fig. 5.

These pivoted sections are resiliently urged toward each other by means of springs 19, surrounding pins 20 and 21 carried respectively by one of the sections and a post 22 depending from the cover plate, such springs being interposed between the funnel sections and such posts.

With such a construction, a cigarette butt, as indicated at x in Fig. 5, may be inserted through

one of the openings 14 into the divided funnel beneath the same, and, after being extinguished as above explained, may be pushed on down through the funnel into the receptacle, the pivoted sections of the funnel yielding laterally so as to permit the cigarette to pass through, as illustrated in Fig. 5.

What I claim is:

1. In an ash tray and cigarette extinguisher, the combination with a receptacle, of a one piece cover therefor pivotally supported to swing about a horizontal axis extending across the middle thereof, and a vertically disposed funnel carried by said cover at one side of said axis and having its lower open end substantially smaller than the diameter of a cigarette, so that when a lighted cigarette is placed therein, it will be supported and extinguished, and the ashes only will pass through.

2. In an ash tray, the combination with a receptacle, of a cover disposed within and substantially closing the top thereof, said cover being pivotally supported to swing about a horizontal axis extending across the middle thereof, an open funnel carried by said cover at one side of said axis and constituting a weight unbalancing said cover so that it tends to turn about said axis, and a stop for normally maintaining said cover in horizontal position.

3. In an ash tray, the combination with a receptacle, of a cover disposed within and substantially closing the top thereof, said cover being pivotally supported to swing about a horizontal axis extending across the middle thereof, an open funnel carried by said cover at one side of said axis, and said cover, at the other side of said axis being shaped to provide a cigarette-receiving trough extending parallel with said axis, and means for normally maintaining said cover in horizontal position.

4. In an ash tray, the combination with a receptacle, of a cover disposed within and substantially closing the top thereof, said cover being pivotally supported to swing about a horizontal axis extending across the middle thereof, said cover having an opening, a funnel carried by said cover in alignment with said opening, said funnel comprising a pair of independently pivoted sections and its lower small end being smaller than the diameter of a cigarette, and means for yieldingly holding said sections together so that they may move apart to permit a cigarette to be pushed through the funnel into said receptacle.
